Charles L. Gill,
ATTORNEY

UNITED STATES PATENT OFFICE.

VICTOR GAERTNER, OF NEW YORK, N. Y.

DESIGN FOR AN ARTICLE OF HOLLOW TABLEWARE.

57,833.

Specification for Design.

Patented May 10, 1921.

Application filed November 11, 1920. Serial No. 423,488. Term of patent 7 years.

To all whom it may concern:

Be it known that I, VICTOR GAERTNER, a citizen of the United States, residing at New York city, in the county and State of New York, have invented a new, original, and ornamental Design for an Article of Hollow Tableware, of which the following is a specification, reference being had to the accompanying drawings, forming a part thereof, and in which:—

Figure 1 is a top view, and
Fig. 2 a side elevation of an article of hollow tableware embodying my design.

I claim:

The ornamental design for an article of hollow tableware, as shown.

VICTOR GAERTNER.
